CLAIM

The ornamental design for a kabob pet treat, as shown and described.

DESCRIPTION

FIG. 1 is a front, top and right side perspective view of a kabob pet treat according to the new design;

FIG. 2 is a back, bottom and left side perspective view thereof;

FIG. 3 is a front view thereof;

FIG. 4 is a back view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in FIGS. 1, 2 and 4-8 illustrate portions of the kabob pet treat that form no part of the claimed design.

1 Claim, 4 Drawing Sheets
